UNITED STATES PATENT OFFICE.

IRVIN M. RITTER, OF BUCHANAN, MICHIGAN.

MOVING-PICTURE FILM.

1,360,441.

Specification of Letters Patent. Patented Nov. 30, 1920.

Application filed June 14, 1919. Serial No. 304,127.

To all whom it may concern:

Be it known that I, IRVIN M. RITTER, a citizen of the United States, residing at Buchanan, in the county of Berrien and State of Michigan, have invented certain new and useful Improvements in Moving-Picture Films, of which the following is a specification.

Films as generally provided for kinetoscopes and moving picture mechanism are of a nature to break readily and thereby cause considerable annoyance and delay besides making a fire possible because of the delay in the feed of the film, the latter being exposed to the heat engendered by the light rays, by means of which the picture is projected.

The present invention has for its purpose to reinforce the edges of the film in a manner to not detract from the flexibility of the film or add to its bulk or require any change in the feeding mechanism of the kinetoscope or picture mechanism.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

Referring to the drawing hereto attached,

Figure 1 is a front view of part of a moving picture film embodying the invention. Fig. 2 is a sectional detail on the line $x-x$ of Fig. 1, showing the part on a larger scale.

Fig. 3 is a transverse section on the line $3-3$ of Fig. 1 showing the part on a larger scale.

Corresponding and like parts are referred to in the following description and indicated in the several views of the drawing by like reference characters.

The body of the film is designated by the numeral 1 and may be of any material, commonly employed in the manufacture of films of kinetoscopes and moving picture machines. Along each edge, the film is provid-

ed with openings 2 for receiving the cogs or teeth of the sprocket wheels, by means of which the film is positively fed when in active operation. In accordance with the present invention, a line of stitching 3 is provided at each edge of the film and just inside of the line of openings 2, said stitching being preferably of the lock type, such as made by a sewing machine having upper and lower treads. While stitching of the lock type is preferred, it is to be understood that stitching of any variety may be employed. By having the stitching adjacent the rows of openings and just inside thereof, the film is prevented from parting laterally, should the break tend to start at any one of the sprocket openings 2. The stitching necessarily projects slightly beyond the surface of the film and besides acting as a reinforcement to prevent lateral parting of the film, also serves as means to prevent injury to the sensitized surface of the film, so that such surface is not liable to become scratched or worn by contact with parts of the mechanism, or by adjacent winds or portions of the films rubbing against each other. In addition to the lines of stitching 3, the outer edges of the film are reinforced, as indicated at 4, by the application thereto of a cement which may be of any nature to give a finished appearance to the edges of the film and materially strengthen and reinforce the same.

Having thus fully described my invention, what I claim as new and desire to secure by Letters Patent is:

A moving picture film having its edge portions reinforced by the application of a suitable cement thereto and having rows of sprocket openings adjacent the reinforced edges and having lines of stitching just inside of the rows of sprocket openings.

In testimony whereof I affix my signature in presence of two witnesses.

IRVIN M. RITTER.
